CLAIM

The ornamental design for a cart for house and garden tools, as shown and described.

DESCRIPTION

FIG. 1 is a left side elevational view of a cart for house and garden tools showing my new design, the right side being a mirror image thereof;

FIG. 2 is a front elevational view thereof;

FIG. 3 is a top plan view thereof;

FIG. 4 is a rear elevational view thereof;

FIG. 5 is a bottom plan view thereof; and

FIG. 6 is a front and left side perspective view thereof.
